METHOD FOR THE RECOVERY OF
HYDROCARBON VAPORS

Robert F. Hartman, El Segundo, Edward H. Lynch, Manhattan Beach, and Laverne P. Elliott, Berkeley, Calif., assignors, by direct and mesne assignments, to California Research Corporation, San Francisco, Calif., a corporation of Delaware

Application January 31, 1955, Serial No. 484,962

10 Claims. (Cl. 183—115)

This invention relates to a method for recovering hydrocarbon vapors from a vessel containing air and normally liquid hydrocarbons, and, more particularly, to a method for recovering valuable hydrocarbons vaporized from a mixture of normally liquid hydrocarbons as they are loaded into a container.

In the loading of liquid hydrocarbons into tanks, trucks, ships and the like, normal operations are to displace the air contained in these empty vessels with the liquid, allowing the air to be vented into the atmosphere. However, even when loading higher boiling hydrocarbon mixtures such as gas oils, a certain amount of vaporization of the low boiling components in the oil occurs, thus resulting in the release of these vapors to the atmosphere along with the air. The efflux of vapor from the vessel increases as the temperature increases and as the boiling range of the liquid mixture decreases, so that when the liquid is gasoline, considerable quantities of C₄ and C₅ hydrocarbons are discharged through the venting apparatus. With the problem of air pollution being one of concern to the petroleum industry as well as the public, it would be highly desirable to prevent the escape of these vapors, thus reducing the "smog" conditions existing in many parts of the world. Furthermore, by venting these hydrocarbon vapors into the atmosphere, these valuable hydrocarbons are irretrievably lost.

Accordingly, it is an object of the present invention to provide a method for recovering substantially all of the hydrocarbons vaporized during the loading of normally liquid hydrocarbon mixtures into tanks and the like, thus preventing the discharge of such vapors into the air as contributors of atmospheric pollution.

Further objects will be apparent from a consideration of the description to follow.

According to the present invention, an air-vapor mixture is recovered from a vessel and passed into a saturation zone wherein the mixture is substantially saturated with respect to its hydrocarbon content by contacting the mixture with a liquid stream of normally liquid hydrocarbons. The saturated air-vapor mixture is withdrawn from the saturation zone, compressed to a pressure in the range of from about 50 to 1000 p. s. i. g., and introduced into a contacting zone such as an absorber, mixer, or the like, wherein the mixture is intimately contacted with a liquid stream of normally liquid hydrocarbons. From the contacting zone are recovered a gaseous phase which is relatively free of hydrocarbon vapors, and the liquid hydrocarbon stream introduced into the contacting zone as enriched with hydrocarbons from the compressed air-vapor mixture. It has been found that the present invention is particularly effective in recovering vaporized components of gasoline, and thus, the liquid hydrocarbon employed in the saturation and contacting zones is preferably a petroleum fraction boiling in the gasoline range.

The invention can be more clearly understood by reference to the appended drawing which is a diagrammatic illustration of a process flow suitable for the practice of

2

the present invention. Since the present invention is particularly applicable to gasoline loading operations, the drawing shows one embodiment of the subject invention as applied to tank truck gasoline loading facilities. No attempt is made to indicate valves, control equipment, and the like, since the location thereof can readily be supplied by those skilled in the art.

Referring to the drawing, filling operations are conducted by passing gasoline from storage tank 10 through line 11, pump 12, and line 13 into tank truck 14. In passing into the truck, some of the lighter components of the gasoline are vaporized into the air contained in the vessel, This air-vapor mixture is collected from the vessel, for example, by means of a collapsible fitting that 15 is inserted in a vent in the vessel which, when expanded, forms a vapor-tight collecting device, and is then passed through flexible hose 15, line 16, flame arrester or fire check 17, and line 18 into saturation pot 19, the latter comprising a saturation zone.

20 In the saturation pot, the air-vapor mixture is intimately contacted with gasoline entering the pot from tank 10 through line 11, pump 12, line 13 and line 20. This contacting step serves two purposes, the first being to saturate the air-vapor in respect to its hydrocarbon content 25 so as to prevent the formation of an explosive mixture, thereby eliminating a potential hazard in the subsequent treatment of the air-vapor mixture. The second purpose, which is applicable to a preferred embodiment of the present invention, is that upon the passage of the 30 gasoline into the pot, a certain amount of vaporization of light hydrocarbons contained in the gasoline occurs, the liquid gasoline removed from the pot by line 21 thus being depleted of these "light ends," thereby improving its absorbing ability for use in a subsequent treating step.

35 As noted before, the gasoline is removed from the pot by line 21, from which it is pumped by pump 22 into line 23, from which latter line it can be returned to storage tank 10 by lines 24 and 36, or, preferably, is passed by line 23 to an absorber hereinafter described.

40 The saturated air-vapor mixture is passed from pot 19 by lines 25, 37, and 27 to compressor 28, or, more desirably, by line 25 into gas holder 26, as shown in the drawing. The gas holder is preferably a vessel that takes in fluctuating amounts of gas but discharges only a constant, controlled amount. An example of such a holder is a spherical vessel which has a hemispherical flexible membrane on the inside, the outer edge of the membrane being fastened to the shell of the sphere at the equator. The air-vapor mixture is stored between the membrane 45 and the shell.

50 From the gas holder 26 the air-vapor mixture is passed by line 27 into a compressor 28 wherein the mixture is compressed to a pressure in the range of from about 50 to 1000 p. s. i. g., and preferably in the range of from 55 about 100 to 300 p. s. i. g. In the form shown in the drawing, this is accomplished by passing the vapor from holder 26 by line 27 into the first-stage 28a of compressor 28, with the partially compressed mixture then being passed through line 29 into interstage cooler 30 (wherein the mixture is cooled preferably to a temperature below about 275° F. by indirect contact with gasoline, the source of the latter being discussed below). The cooled air-vapor mixture is then passed by line 31 into the second-stage 28b of the compressor from which it is 60 removed at the desired pressure by line 32 and passed into absorber 33, the latter comprising a contacting zone.

65 In the absorber 33 the mixture is intimately contacted with a normally liquid hydrocarbon, desirably gasoline, or, in a preferred manner, with the light hydrocarbon depleted gasoline from the saturation pot 19 which is passed into the absorber by line 23. This gasoline absorbs over 75% by weight of the hydrocarbons contained in the air-

hydrocarbon vapor mixtures displaced from the truck 14 through line 16 so that upon removal of the gaseous phase from the absorber by line 34, less than 25% of the hydrocarbon vapors recovered from the truck are lost. The liquid gasoline, now enriched in light hydrocarbons, is removed from absorber 33 by line 35 and is passed through cooler 30 where it cools the partially compressed air-vapor mixture from the first-stage of the compressor 28 by indirect heat transfer, after which the gasoline is discharged into storage tank 10 by line 36. In this embodiment of the invention, the heat absorbed by the gasoline during the absorbing and cooling stages is dissipated in storage tank 10 which acts as a heat sink.

As noted and described above, a gas holder 26 is included in the preferred embodiment of the present invention. Since the loading of tanks, trucks, and ships is an intermittent operation, it is apparent that the collection of vapors is also of the same nature and thus, if a gas holder is not employed, the recovery facilities will be constantly starting and stopping to handle the surges of recovered vapors. Such intermittent operation requires somewhat complicated instrumentation and control equipment and the occasional attendance by a trained operator. However, the installation of a gas-holding vessel of the vapor-balloon type previously described permits the retention of these intermittent surges while allowing a constant, controlled amount of vapor to be discharged from the vessel to the compressor. Thus, an easily instrumented continuous operation of the recovery facilities is effected. Furthermore, by operating continuously, the lines, compressor, and control apparatus can be reduced in size from that required if intermittent operation is employed.

The operation of the present invention, as applied to the embodiment of the process illustrated in the appended drawing, is shown in the following example.

Example

Gasoline, with an initial boiling point of 95° F. and an end point of 410° F., is passed at a rate of 90,000 gallons/hr. into a tank truck 14. From the truck is displaced typical air-hydrocarbon vapor mixture of the following composition:

Component	Vol. Percent	Lb./hr.
Air.....	65.0	100.0
C ₃ Hydrocarbons.....	1.7	4.0
C ₄ Hydrocarbons.....	17.5	54.0
C ₅ Hydrocarbons.....	10.5	40.2
C ₆ Hydrocarbons.....	5.3	23.6
Total Hydrocarbons.....	35.0	121.8

The air-vapor mixture is passed into saturation pot 19 and contacted with gasoline from storage tank 10 entering said pot at a rate of 1200 gals./hr. The saturated mixture is passed into gas holder 26, from which it is passed to compressor 28 where it is compressed at a rate of 1980 cu. ft./hr. to a pressure of 205 p. s. i. g. The mixture, with the following composition, is cooled to a temperature of 250° F. in cooler 30 and then passed into absorber 33.

Component:	Vol. percent
Air	70.0
C ₃ Hydrocarbons	1.8
C ₄ Hydrocarbons	17.2
C ₅ Hydrocarbons	8.9
C ₆ Hydrocarbons	2.1
	100.0

In the absorber, the mixture is contacted with gasoline pumped from saturation pot 19 at a rate of 1200 gals./hr. and a pressure of 205 p. s. i. g. From the absorber the liquid gasoline phase is returned to tank 10 via cooler 75

while the gaseous phase is passed by line 34 into the atmosphere. The latter phase has the following composition:

Component	Vol. Percent	Lb./hr.
Air.....	95.0	100.0
C ₃ Hydrocarbons.....	0.2	0.3
C ₄ Hydrocarbons.....	2.9	6.1
C ₅ Hydrocarbons.....	1.0	2.0
C ₆ Hydrocarbons.....	0.9	3.0
Total Hydrocarbons.....	5.0	12.0

From the above example it can be seen that over 90% (by weight) of the hydrocarbons contained in the air-vapor mixture displaced from the tank truck are recovered and retained in the system, while less than 10% of the hydrocarbon vapors which would normally be vented to the atmosphere are so released through line 34. Thus, the objects of the present invention are realized, in that recovery of valuable hydrocarbons displaced from the truck is substantially complete. Furthermore, the absorbing liquid here employed is the same stock as is supplied to the truck, thus avoiding the stripping operations that would otherwise be necessary if the vapors were absorbed in a special liquid of a differing boiling range such as sponge oil or the like.

We claim:

1. A method of recovering light hydrocarbon vapors from a vessel containing said vapors in admixture with air, which comprises recovering the air-vapor mixture from said vessel; substantially saturating said mixture in respect to its hydrocarbon content by contacting said mixture in a saturation zone with a liquid stream of normally liquid hydrocarbons; compressing the resulting saturated mixture to a pressure in the range of from about 50 to 1000 p. s. i. g.; contacting the resulting compressed mixture in a contacting zone with a liquid stream of normally liquid hydrocarbons; and recovering from said contacting zone an overhead gaseous phase which is relatively free of hydrocarbon vapors and can be vented without appreciable contamination to the atmosphere, and, as bottoms from said contacting zone, the liquid hydrocarbon stream introduced therein as enriched with hydrocarbons from the compressed mixture.

2. The method of claim 1 wherein the substantially saturated mixture is compressed to a pressure in the range of from about 100 to 300 p. s. i. g.

3. The method of claim 1 wherein the liquid hydrocarbon streams employed are gasolines.

4. A method of recovering light hydrocarbon vapors from a vessel containing said vapors in admixture with air, which comprises removing the air-vapor mixture from said vessel and contacting said mixture in a saturation zone with a liquid stream of gasoline; recovering from said zone an air-vapor overhead fraction substantially saturated with respect to its hydrocarbon content and a gasoline bottoms fraction; passing said overhead fraction into a gas holder; continuously withdrawing said saturated air-vapor mixture from said gas holder and compressing the mixture to a pressure in the range of from about 50 to 1000 p. s. i. g.; passing the resulting compressed mixture into a contacting zone wherein it is contacted with liquid gasoline; and continuously recovering from said contacting zone an overhead gaseous phase which is relatively free of hydrocarbon vapors and can be vented without appreciable contamination to the atmosphere, and, as bottoms from said contacting zone, a hydrocarbon-enriched liquid stream of gasoline.

5. The method of claim 4 wherein at least a portion of the gasoline bottoms fraction recovered from the saturation zone is passed into the contacting zone so as to contact the compressed air-vapor mixture.

6. The method of claim 4 wherein the contacting zone is an absorber.

7. The method of claim 4 wherein the saturated air-vapor mixture is compressed to a pressure in the range of from about 100 to 300 p. s. i. g.

8. In a truck loading station wherein gasoline is intermittently passed from a storage tank into a vessel upon a truck, the method of avoiding contamination of the atmosphere by the hydrocarbon vapors displaced from said vessel as the same is filled with gasoline, which comprises removing the air-vapor mixture from said vessel and contacting said mixture in a saturation zone with a liquid stream of gasoline; recovering from said zone an air-vapor overhead fraction substantially saturated with respect to its hydrocarbon content, and a gasoline bottoms fraction; passing said overhead fraction into a gas holder; continuously withdrawing said saturated air-vapor mixture from said gas holder and compressing the mixture to a pressure in the range of from about 50 to 1000 p. s. i. g. in a compressor; passing the resulting compressed mixture into an absorber wherein it is contacted with at least a portion of the liquid gasoline bottoms fraction recovered from said saturation zone; and continuously recovering from said absorber an overhead

5

gaseous phase which is relatively free of hydrocarbon vapors and can be vented without appreciable contamination to the atmosphere, and, as bottoms from said absorber, a hydrocarbon-enriched stream of gasoline.

10

9. The method of claim 8 wherein the saturated air-vapor mixture withdrawn from the gas holder is compressed to a pressure in the range of from about 50 to 1000 p. s. i. g. in a multi-stage compressor, said air-vapor mixture being cooled between at least one of the compression stages in at least one interstage cooling zone.

15

10. The method of claim 9 wherein at least a portion of the hydrocarbon-enriched bottoms stream of gasoline recovered from the absorber is passed into at least one of the interstage cooling zones so as to cool, by indirect heat exchange, the air-vapor mixture as it passes between the stages of the multi-stage compressor.
